UNITED STATES PATENT OFFICE.

HENRY F. STARRETT, OF CHICAGO, ILLINOIS, ASSIGNOR TO STARRETT MANUFACTURING COMPANY, OF CHICAGO, ILLINOIS, A CORPORATION OF ILLINOIS.

PANEL BOARD AND PANEL-BOARD CONSTRUCTION.

Application filed November 10, 1919, Serial No. 337,068. Renewed June 16, 1924.

This invention relates to panel boards and panel board construction and more particularly to panel boards used in electric lighting systems, and in systems of residence, apartment, factory, and all other types of building wiring.

This invention is a further development of the invention disclosed in my Patent No. 1,294,185, issued February 11th, 1919, and 10 comprises an enlargement of the "knock-down" form of panel board, the units of which are standardized stock parts which may be readily assembled to provide a panel board of any desired capacity and adapted 15 to any one of a plurality of electric wiring systems within the regular requirements of the trade.

For the purpose of adapting the standardized stock units to any one of a plurality of 20 electric wiring systems, the unit constructed for stock purposes is what may be termed a neutral unit; that is, a unit comprising a standardized base which may be either blank, or may carry circuit controlling equipment, 25 and which in the condition that it is carried in stock is not designed for any particular type of electric wiring system. These units, however, are designed and constructed so that they possess an inherent capacity for 30 development, by the addition of other standardized means, whereby, when assembled into a panel board containing either one or a plurality of said neutral units, the units can be interconnected by the use of said standardized means into any one of a plurality 35 of electric wiring systems. The panel board unit system described herein, therefore, distinguishes from the invention disclosed in my aforesaid patent, primarily in that in 40 the present invention the unitary stock elements of the systems are neutral with respect to the ultimate panel board electric wiring system and can be adapted and connected by standardized means into any one 45 of a plurality of such systems; whereas, in the invention of my aforesaid patent each unit is individual to and adapted to but one particular form of panel board electric wiring system. The inherent improved construction of the units, standardized conducting bars and main bus bars of this system likewise serves to better adapt the system for the construction of panel boards of increased current carrying capacity.

55 All the component elements and parts required for the construction of the panel board, which is constructed according to the teachings of this invention, can be made in quantity by the manufacturer with consequent lessened cost and can be carried in stock to enable quick assembly at minimum cost. The manufacturer can consequently establish throughout the country branch distributing houses where these various component parts can be carried in stock and at which substantially any desired type of panel board can be constructed with a minimum of labor and time.

The manufacturer may carry in stock at the factory and at these branch distributing 70 houses portable standardized neutral panel units of varying capacity which can be readily united to construct panel boards of a capacity larger than any of the standard portable units, and which are adapted to be 75 included by the addition of selected standardizing parts into any one of a plurality of electric wiring systems. However, since these portable neutral units are constructed for interchangeability and the assembly 80 thereof is an exceedingly simple operation, a large panel board can be maintained, if desired, in a portable disassembled or "knockdown" state until it has been transported to the place where it is to be installed. 85 The panel board problem, including all its different variable features, as for example, capacity and ultimate method of interconnection to the power leads and distributing system, is thus reduced to a manufacturing 90 and commercial proposition and removed almost entirely from the domain of engineering.

Briefly stated, a built up panel board of the type hereinafter specifically described 95 comprises either one, or a plurality of standard basic neutral units equipped with either branch unit fuse receptacles only or with branch circuit switches and fuse receptacles. These units are constructed in varying capacities, preferably four-circuit, six-circuit, 100 eight-circuit, and ten-circuit units, which units may be used either individually or in any desired combination to obtain a panel board of the desired capacity. Each of said 105 units, depending upon the ultimate electric wiring system to be utilized, is also fitted to receive standardized conducting bars which serve as the interconnecting links between the conducting bars of the neutral 110

unit and the main bus bars. Associated with each panel board, depending upon the ultimate service desired, is a tail unit such as described in my aforesaid patent, which 5 tail unit carries the terminal equipment, either fuses or switches or combination fuses and switches, or any other desired equipment, adapted to the particular type of wiring system which is to be connected to the panel board. The system, therefore, 10 contemplates and requires neutral basic standardized units for each capacity of unit that it is desired to carry in stock for two equipments—the one in which fuse receptacles only are required, and the other in which combined fuse receptacles and switches are desired. With these units, the 15 standardized conducting bars and suitable common bus bars, which can be connected to the equipment without the necessity of any lateral bends, any desired capacity of panel board can be constructed and equipped for connection into electric distributing systems of either the two-wire, three-wire, three-phase, four-wire three-phase or convertible 20 two to three-wire and three to two-wire type and all commercial variations therefor.

It is one of the principal objects of this invention, therefore, to produce a system 30 of standardized commercial production in the panel board art whereby panel boards of any capacity can be built up from "knock-down" standardized units and which units, when thus assembled into a panel board, can 35 be combined with standardized means so that they can be interconnected into any one of a plurality of commercial electric wiring systems.

It is another object of this invention to 40 so construct and design these standardized units and the associated standardized inter-connecting means that the standardized commercial bus bar strap can be used to inter-connect the equipment of the units without 45 the necessity of any lateral bends in the bus bars, thereby avoiding the complicate form of the bus bar strap. This obviously reduces the work of constructing the main bus bars for the panel board to the exceedingly simple and inexpensive operation of 50 cutting the strap and making occasional vertical bends. Consequently, the necessary main bus bar can be readily cut and fitted without complicated tools, and this operation 55 can be easily, readily, and cheaply performed either at the factory or at the branch distributing house.

A further object of this invention consists 60 in the production of an improved form of basic unit of the neutral type.

Another object comprises the production 65 of an improved construction of panel board barrier frame.

Another object consists in the production 70 of an improved form of switch cover plate

utilized with the switches and panel boards of this type when the dead front type of panel board is desired.

A still further object comprises the provision of simple means whereby the panel 75 board can be easily and properly centered and positioned in the panel box.

Other objects and advantages of the invention will be apparent from the accompanying description setting forth in more 80 detail such objects, features, and advantages and the manner in which the same are realized and also from the accompanying drawings illustrating an embodiment of the invention, as well as modifications of certain 85 features thereof.

Referring to the drawings—

Fig. 1 is a view in front elevation of an assembled panel board positioned in a panel box with the inner door of the panel box 85 cover thrown open to expose to view the branch circuit switches;

Fig. 22 illustrates the side view of one of the barrier units and shows the means utilized for re-enforcing said side and interconnecting various sections thereof;

35 Fig. 23 is a view in perspective illustrating the corner iron which receives the sides of the barrier frame and illustrates the method of connecting the re-enforcing member of the side with said corner iron;

40 Fig. 24 is a vertical section through the cover of the panel box illustrated in Fig. 1 and illustrates the means utilized for preventing access to the fuse receptacles when the inner door of the cover of the panel box 45 only is opened;

Fig. 25 is an enlarged perspective view of the metallic receiving pockets used to position the assembled panel board in the panel box enclosure;

50 Fig. 26 is a vertical section through the branch switch circuit cover plates and illustrates the means for interconnecting and interlocking these plates whereby the individual plates when assembled are rigidly held in position and give the general appearance of one continuous plate;

Fig. 27 is a rear view of the upper portion 55 of the assembled panel board shown in Figs. 1 to 4 inclusive with the main bus bars and the conducting bars used to connect the main bus bars to the neutral units removed;

60 Fig. 28 is a rear view of the assembled panel board shown in Figs. 1 to 4 inclusive assembled with standardized means to adopt the board to a two-wire distributing system;

Figs. 29 and 30 are enlarged perspective views of the standardized conducting bars used to interconnect the main bus bars and the conducting bars or plates of the neutral unit for a two-wire distributing system; 70

Fig. 31 is a rear view of the panel board illustrated in Figs. 1 to 4 inclusive assembled with standardized means for a three-wire distributing system.

Fig. 32 is a plan view of the tail unit used 75 with the assembled panel board when wired for a three-wire or three-phase distributing system.

Fig. 33 is a plan view of the tail unit utilized with the panel board adapted for a 80 three-wire distribution system when converted to a two-wire distributing system;

Fig. 34 to 37 inclusive are enlarged perspective views of the standardized conducting bars used to interconnect the conducting bars or plates of the neutral units with the main bus bars of the panel board when adapted for a three-wire distributing system; 85

Fig. 38 is a view in side elevation of a 90 common bus bar;

Fig. 39 is a rear view of the assembled panel board illustrated in Figs. 1 to 4 inclusive assembled with standardized conducting means for a three-phase distributing 95 system;

Fig. 40 to 43 inclusive are enlarged perspective views of the standardized conducting bars used to interconnect the conducting bars or plates of the neutral units with the 100 main bus bars of a three-phase distributing system;

Fig. 44 is a rear view of the assembled panel board illustrated in Figs. 1 to 4 inclusive assembled with standardized means 105 for a four-wire three-phase distributing system;

Fig. 45 is a front elevation of the tail unit used with the assembled panel board when wired for a four-wire three-phase distributing 110 system; and

Fig. 46 to 49 inclusive are enlarged perspective views of the conducting bars used to interconnect the conducting bars or plates of the neutral units with the main bus bars. 115

According to this invention a plurality of assembled units are provided which may be manufactured in stock form and which may be used for supplying a panel board for any capacity desired and adapted to be built up 120 for interconnection into any one of a desired plurality of electric wiring systems. As hereinbefore stated, it is preferred to construct these units for a capacity of four, six, eight, and ten circuits, but for the sake of brevity in the description, and in order to curtail the number of necessary illustrations, but one capacity; that is, the four circuit unit, has been illustrated in detail.

The assembled panel board illustrated in 125

Figs. 1 to 4, as will be clearly evident from Fig. 3, consists of two such four circuit units—10 and 11—and two six circuit units—12 and 13. Obviously, this assembled panel board is consequently designed for an ultimate capacity of twenty circuits, and if any other capacity is desired, the standardized units of four, six, eight, and ten circuits can be readily combined to obtain any desired ultimate capacity.

As illustrated in these figures, the assembled panel board is positioned in a panel box enclosure consisting of the base portion 14 and the cover portion 15. The cover portion 15 is secured to the flanges 16 on the base portion by means of screws such as 17. The cover portion 15 is equipped with a double door, the outer door 18 being of a size sufficient to cover the fuse receptacles and switches mounted on the panel board, and the inner door 19 being of a size sufficient to cover only the branch circuit switches. The inner door 19 is hinged to the outer door at 20 and 21; whereas, the outer door 18 is suitably connected to the cover frame 22 by means of hinges such as 23. The cover frame 22 serves as a cover for the gutter 24 surrounding the assembled panel board, the panel board being separated from the gutter by a barrier frame 25 consisting of the end pieces 26 and 27, and the side pieces 28 and 29.

The frame 22, as will be evident from Figs. 2 and 3, serves to cover completely the gutter 24 and the enclosing barrier frame 25 whereby all the branch fuse receptacles and switches will be exposed to view when the outer door 18 is opened, as illustrated in Fig. 2, and the branch circuit switches only will be exposed to view when the inner door 19 is opened. The inner door 19 is equipped with a suitable catch 30 by means of which it can be fastened to the outer door, and preferably this door is not fitted with a lock so that the branch circuit switches covered by said door will always be accessible. The outer door, on the other hand, is equipped with a lock 31 to lock this door to the frame 22, and whereby access to the fuse receptacles can be obtained only by those who have possession of the key, which key will be retained by the expert electrician or those authorized to make fuse plug changes.

The individual standard units 10, 11, 12, and 13 are mechanically connected, as hereinabove described, to suitable channel bars such as 32 and 33, which channel bars are secured to the bottom of the base 14 by means of screws such as 34. It will consequently be apparent that the assembled panel board as a whole can be readily removed or positioned in the panel box enclosure. In order to facilitate the positioning of the assembled panel board in the panel

box enclosure so that the respective doors 18 and 19 and the frame 22 of the cover 15 will be properly positioned and centered with respect to the panel board, mechanical receiving pockets or shoes such as 35 are fitted on the bottom of the base 14 of the housing, as will be more specifically herein-after described.

As illustrated in Figs. 1 to 4 inclusive, the assembled panel board consists of the portable interfitting basic units 10, 11, 12, and 13 and a suitable tail unit such as 36, the tail unit being separated from the rest of the panel board by a barrier 37. The assembled panel boards consisting of the standardized units 10, 11, 12, and 13 consequently have their ends enclosed by the barriers 26 and 37, which snugly fit against the end of the two units 10 and 13 respectively and thus close off the end pieces of apparatus on these units from the gutter 24 and the tail unit respectively. In order to completely enclose all potential and current carrying parts of the panel board, so as to prevent both accidental and deliberate contact therewith, the branch circuit switches are covered with plates such as 38, through which the operating elements of the switch mechanisms project. These cover plates for the switches will be described more in detail hereinafter.

In order to shut off completely the fuse receptacle mounted on the units, from the individual opening provided by the inner door 19 used for the purpose of operating the switches, the outer door 18, has secured thereto the downwardly extending flanges 39 and 40, preferably constructed of sheet steel (see Figs. 2 and 24). These flanges, when the outer door is closed, completely close the space between the switch covers 38 and the door, and thus prevent any deliberate effort to reach the fuse receptacle and fuse plugs, and likewise prevent the accidental dropping of foreign matter into the space occupied by the fuse receptacles positioned on the units. The flanges 39 and 40 are tapered as shown in Fig. 24, whereby the desired sized opening for the switches may be obtained without unnecessarily increasing the width of the panel board to prevent interference between the fuse receptacles and their associated fuse plugs and the flanges or partitions 39 and 40.

Structurally, all the basic units illustrated are substantially the same, differing only in capacity and possibly in width, the units which are to be used for fuses only being preferably made somewhat narrower than the ones with which switches and fuse receptacles are to be used, so that a description of one of said units will serve for all.

The standard portable basic neutral unit used to build up the panel board of the four circuit capacity is illustrated in Figs. 130

5 and 6. This unit is preferably made of a flat slab or base 41 of insulating material, preferably of some non-brittle material, such as pitch-asbestos compound which can 5 be readily molded in the desired shape or any other such suitable insulating material that can be obtained on the market. Such a molded base possesses the advantages of being light in weight and because of the inherent advantages of the material employed 10 can be made in much smaller sizes and weight for the same capacity of panel board than slate or like brittle material. Likewise, such a molded base, when it leaves the 15 mold, is a finished article equipped with all the perforations and any special shapes which are desired in the finished article.

The base 41 (see Figs. 5, 6, and 27) is provided with a series of perforations such as 20 42, which are adapted to receive screws 43, the threaded ends of which are connected to conducting bars such as 44 mounted on the front face of the unit. These conducting bars 44 are fitted with threaded apertures such as 45 which are adapted to receive 25 screws such as 46 of the fuse receptacles interconnecting the center contact of said fuse receptacles with the conducting bars 44, the screw 46 constituting the center contact of 30 the fuse receptacle. The threaded shell contact 47 of the fuse receptacle is directly connected to a branch circuit terminal 48, illustrated in Figs. 2 and 10, and to be described more in detail hereinafter.

35 In addition to the perforations 42 the base unit 41 is equipped with four perforations such as 49, preferably positioned near the four corners of the unit, said perforations receiving screws such as 50 to receive the 40 cross bars 51 of the re-enforcing frame for the unit. The base 41 is also fitted with suitable indentations in its top surface under each one of the perforations 45 fitted in the conducting bar such as 44 mounted 45 thereon to receive the ends of the screws such as 52, which are used to secure the circuit controlling equipment to the conducting bars.

In addition to the aforesaid perforations, 50 the neutral unit is fitted with a plurality of slots such as 53, one of said slots being provided for each pair of branch circuit leads. These slots on the rear face of the panel board (see Figs. 7 and 12) are enlarged and 55 provided with an outwardly extending sloping or tapering wall 54, said slope or taper being provided so that the conducting bar 55, which is positioned in each one of such slots 53, can be readily inserted and positioned in proper place through the narrow aperture 56 cut into the top face of the standard neutral panel. In a four circuit standard neutral unit, as illustrated in Figs. 5 and 6, only two complete slots such as 53 60 are provided, these slots being positioned as

shown in Fig. 6 on substantially the middle portion of the panel.

At the edge of the panel slots such as 57 are provided, said slots being in all respects identical to the slots 53 but only half the 70 width thereof. Consequently, when two standard neutral units are positioned one above the other, the end slots 57 in such units combine to form a slot similar to the slot 53. The slots 53, as hereinbefore mentioned, are provided to receive the conducting plates or bars 55, illustrated in detail in Fig. 8. These conducting plates 55 are fitted with conducting arms, one of which—58—rests on the front face of the panel, and 80 the other of which—59—is positioned in a groove 60 cut in the lower face of the panel. The arm 59 can obviously be either positioned in a groove such as 60 cut in the back face of the standard unit or may be designed so as to be placed on the back surface of said unit, under which circumstances the groove 60 can be eliminated. The arm 58 and arm 59, which rest on either side of 85 the standard unit, are interconnected and 90 integral with the conducting link 61, which is tapered so that the conducting plate 55 can be readily inserted and positioned into the perforation 53 in the base of the standard unit.

Conducting plates or bars such as 55 are positioned in all of the perforations 53 and in the built up perforations consisting of two perforations 57 mounted end to end, which combine to make perforations such as 53. Whenever the standard neutral unit is not combined with another standard neutral unit so that the end slot or perforation 57 cooperates with another slot or perforation 95 to form a perforation or slot such as 53, the slot or perforation 57 is equipped with a conducting plate or bar such as 62. (See Fig. 9.)

The conducting plate 62, as will be evident from Figs. 8 and 9, is alike in all respects to half of the plate 55 when said plate 55 is divided along its median line. Thus, the conducting plate 62 is fitted with an arm 63 which lies on the front face of the panel unit and an arm 64 which rests in 110 a slot cut in the rear face of the standard unit, each of said arms being of half the length of the corresponding arms 58 and 59 respectively of the conducting plate 55. The arms 63 and 64 of the plate 62 are integral with and interconnected by a conducting strap 65, which strap 65 is of half 115 the width of the corresponding element 61 of the plate 55.

The upper arm 58 of the conducting plate 55 is fitted with threaded perforations such as 66 which are adapted to receive the screws 52, which interconnect the terminals of the switch such as 67 with the conducting bar 55, and thus extend the terminal connection 120 125

of the switch from the front to the rear of the standard neutral panel board unit. The conducting plate 62 is fitted with like perforations serving the same purpose.

5 The arm 59 is provided with threaded perforations 69 adapted to receive standardized conducting means adapted to interconnect the circuit controlling apparatus mounted on the front of the standard panel 10 unit with the main bus bars, as will be hereinafter described. The conducting plate 62 is fitted with a like threaded perforation 69.

The plates 55 and 62 are held in position, after being inserted in the standard neutral 15 panel unit, in any suitable manner, but preferably by means of screws such as 73, which will be readily apparent from inspection of Figs. 5 and 7.

The slots 53 on the rear face of the base 20 unit 41 are provided with elongated depressions such as 70 and 71, which extend along the rear face of the unit 41. These depressions are fitted with perforations such as 72 which extend to the front face of the 25 unit 41 and which receive the screws such as 73 for securing the conducting plates or bars such as 55 and 62 to the unit 41.

As hereinbefore stated, each standard neutral panel unit comprises an insulating base 30 41 and has secured thereto, by means of the screw 50, the re-enforcing bars 51 which extend across the entire rear face of the base 41. These bars 51 are preferably made of steel and, in addition to re-enforcing the 35 base 41 and increasing its rigidity, these bars serve as the interconnecting means for the lateral mounting plates 76 which are secured to the bars 51 in any suitable manner, preferably by welding (see Figs. 20, 21 40 and 24).

The mounting plates 76 consist of a strap of metal, preferably steel, extending along the lateral edges of the base 41 of the unit and are of a substantially U/Z section, the 45 upper arm 77 of which is attached to the cross re-enforcing bars 51 and the lower arm 78 of which, provided with an elongated perforation 79, is utilized to mount the panel unit on the channel irons 32 and 33 hereinbefore referred to.

It will now be evident that in assembling a unit of the type illustrated in Figs. 5 and 6, the insulating base 41 is first fitted with the re-enforcing members 51 by means 55 of the screws 50, whereby the mounting plates 76 are secured to the base 41. The insulating base 41 is next fitted with the conducting bars such as 44 and the conducting plates or bars such as 55 and 62, which are 60 secured to the base 41 by suitable screws such as 73 as hereinbefore described. When the base has been fitted with these conducting bars and the mounting strips, it is ready 65 to receive the desired circuit controlling apparatus. This circuit controlling apparatus

may take the form of any one of the standardized types of fuse receptacles and switches. Thus for example, in Figs. 5 and 6, the standard push button switch, such as 67, has two of its terminals connected, one to the arm 58 of the conducting plate 55, and the other to the arm 63 of the conducting plate 62. The other two terminals of the switch 67 are connected to conducting bars such as 44. Likewise connected to the conducting bars 44 are the screws 46 which constitute the center contact of the two fuse receptacles 48 associated with each one of these push button switches 67.

To those skilled in the art it will be evident from the connection, shown in the upper right corner of Fig. 5, of the fuse receptacle and switch how this apparatus for the entire unit is connected to the various connecting bars and plates associated with the unit. It will also be apparent that the conducting plates 55 serve as a common conductor for one terminal of two circuits. In other words, one terminal of each of two adjacent switches are connected to the arm 90 58 of a common conducting plate 55. The shell contact of the fuse receptacles is carried out to the branch circuit terminals 48 at the edge of the panel unit in any suitable way, preferably by a conducting bar such as illustrated in Figs. 1 and 10. Obviously any one of a large variety of means could be used for wiring the shell contact of the fuse receptacle to the edge of the board and a detailed description of the particular manner in which this is done in the embodiment illustrated is, therefore, not essential. The switches such as 67 when mounted on the panel unit are preferably enclosed in an insulating sleeve such as 75, the details and 100 functions of which are described in my co-pending application Serial No. 337,069, entitled "Panel-board and panel-board construction" filed of even date herewith.

When the circuit controlling apparatus, such as fuses and receptacles, is mounted on the face of the panel unit and interconnected to the conducting plates, such as 44, 55, and 62, the unit is completely assembled in its neutral condition and is adapted to be fitted 110 by the use of standardized conducting means for interconnection with common bus bars adapted to be wired into any one of a plurality of electrical wiring systems.

The perforations and slots with which the insulating base 41 of the standard unit is equipped are so designed and arranged that said unit can be readily fitted and equipped with either the push button type of switch, the knife blade switch, or with the fuse receptacles for plug fuses or cartridge fuses.

Obviously a panel unit equipment would ordinarily be fitted with but one type of equipment, but in order to clearly illustrate the flexibility of the unit and its adapta-

bility to various types of circuit controlling apparatus, such as for example, push button switches, knife blade switches, and plug and cartridge fuses, Figure 10 has been included 6 to show a panel with a composite equipment. This figure illustrates a four circuit unit in which two of the circuits are provided with knife blade switches and cartridge fuses and two with push button 10 switches and plug fuses.

Fig. 11 shows the front view of the panel unit with all the apparatus, with the exception of one knife blade switch removed, whereas Fig. 10 illustrates the same panel 15 unit with the circuit controlling apparatus in position. From an inspection of Fig. 11, it will be evident that the same conducting bars 44 used in Fig. 5 are used in this instance for the push button switch. The 20 same conducting plates 55 and 62 are utilized to carry the circuit of the circuit controlling apparatus mounted on the front of the unit to the rear of the unit. For the push button type switch, the terminals of 25 the switch are secured directly to the conducting bars such as 44, 55, and 62; whereas, for the knife blade switches, as illustrated in Fig. 12, the clip contacts 80 are secured to the conducting plates 62 and 55 30 respectively by a screw such as 81 extending through a standard perforation 81' in the insulating base 41 and the standard threaded perforation in the conducting plates 62 and 65, and is held in place by a conducting plate 82 shown in perspective in Fig. 13, which is fitted with a threaded aperture 83 to receive the end of the screw 81. The plate 82 rides over the base plate 84 of the clip contacts 80, thereby holding the clip 40 contacts in position, and the clip contacts 80 are prevented from turning by means of the downwardly extending arm 85 of the plate 82, which fits into a slot 86 provided in the base 41.

45 The tubular fuses are secured to the base 41 by means of the standard commercial clip contacts ordinarily used in the art, which contacts are formed integral with conducting bars such as 87 and 88. The conducting 50 bars such as 87 are fitted with the threaded perforations 89 and 90, the perforation 89 fitting over the standardized perforation 42 in the base 41, which are adapted to receive the screws such as 43 to secure the conducting 55 bar 87 and its associated clip to the unit. The bar is also fitted with the threaded perforation 90 adapted to receive the clips for mounting the blades of the knife blade switch. In a like manner the conducting 60 bar and its associated clips 88 are equipped with threaded perforations 91 for securing these bars 88 to the base 41.

65 It will now be evident from the descriptions of Figs. 5 to 13 inclusive that the standard neutral panel is perforated and

slotted to receive standardized conducting bars and plates which are adapted to cooperate with suitable interfittings to directly interconnect circuit controlling apparatus of the switch and fuse type illustrated in these 70 drawings with conducting bars or plates extending to the rear face of the unit. Also that the equipment is interchangeably mounted on the face of said units. When the units are thus equipped with this circuit 75 controlling apparatus of the type desired, the circuits of which are carried to the rear face of the standard units, the said units are in a condition as to the ultimate circuit wiring, which may be termed neutral, inasmuch as they are not fitted in this condition to be wired into any particular type 80 of electrical wiring systems. To adapt such a neutral unit to any one of a plurality of 85 commercial electrical wiring systems, the conducting plates 55 and 62 are interconnected and associated with standardized conducting means specific to each particular type of commercial electrical wiring systems, which specific means will adapt the 90 unit for interconnection to that particular electrical wiring system.

Commercial conditions frequently make it desirable that a panel board unit be furnished which is fitted with fuses only and 95 in which the circuit controlling switches illustrated in Figs. 1 to 6 inclusive and 10 and 14 are entirely eliminated. When a unit of this type is desired, it will be obvious that an insulating base for mounting the 100 equipment simpler than the base 41 can be utilized inasmuch as fewer perforations in the said base are necessary because of the elimination of the switches. Further, inasmuch as the switches are omitted, it will be 105 evident that the base can be made considerably narrower, said decrease in the width of base being equivalent to the space ordinarily occupied by the switch. Obviously 110 the bases which are equipped for fuses only can be made of the same width as the bases which carry switches and fuses, but in view of the waste of material involved, and inasmuch as it very seldom, if ever, would 115 occur that an assembled panel board consisting of units in which fuses only are used on some of the units and fuses and switches on the other would be desired, it is preferred to make the units carrying fuses only of a narrower width, as illustrated in Figs. 14 to 17 inclusive. The units there illustrated consist each of insulating bases 92 fitted with a re-enforcing frame equipped with lateral mounting plates 93 similar to those described hereinbefore in connection with 120 the unit carrying switches and fuses.

Fig. 14 shows such a base 92 equipped with fuse receptacles to take fuses 94 of the cartridge type. This base is fitted with perforations such as 95 (see Fig. 16) to re-

ceive the conducting plates such as 96, said plates carrying suitable perforations such as 97 on the arms 98, which rest on the front face of the plate 92 to receive the fuse clips 99. The front face of the plate 92 likewise carries the terminals conducting plate 100 fitted with the fuse clips 101, the terminal clip plate 100 being fitted with a treaded aperture 102 by means of which it is secured to the insulating base 92, by means of a screw extending through from the rear face thereof. The base is also fitted with conducting plates such as 96' which are just half the size of a conducting plate 96, the 10 division being on the median line of the plate 96. Each of the conducting plates 96 and 96', as illustrated in Fig. 16, is fitted with an arm 104 resting on the rear face of the base 92.

20 In order to cover all perforations such as 95 cut in the base 92, a strip of insulating material 105 is secured to the front face of the base 92 by means of screws such as 106, the said plate 105 resting directly on the face 25 of the plate 92 and completely obscuring the perforations 95, as will be evident from Figures 14 and 16.

Fig. 15 illustrates a panel like Fig. 14 equipped with receptacles for plug fuses. 30 In this instance the conducting bars 107 and 107', which carry the circuit from the front face of the base 92 to the rear face thereof and the upper arms thereof 108 are changed in design to meet the conditions 35 necessary to receive the plug fuse receptacles. In other respects this unit is the same as the unit shown in Fig. 14, with the one exception that the plate 109, which covers the perforations 95 adapted to extend the conducting plates 107 and 107' to the rear of 40 the board, is made considerably wider and abuts against the edges of the insulating bases such as 110 of the plug fuse receptacles. The plate 109 in this instance, therefore, insulates and covers all the current and potential carrying conductors exposed on the front face of the base 92 between the fuse receptacles mounted on either side of the unit. With this plate covering completely 45 obscuring these conductors and the use of the housing for the terminal conductors illustrated in Figs. 18 and 19, hereinafter to be described, the unit illustrated in Fig. 15 becomes a dead front unit in which all the 50 current and potential carrying parts are completely covered.

Referring now to Figs. 18 and 19, it will be observed that the plug fuse receptacle 74, which it is preferred to use with this 60 type of equipment, comprises a base portion 112 which is fitted at its forward end with a square aperture 113, said aperture communicating through a cylindrical aperture with the top face of a flange 116 integral with the 65 fuse receptacle 74. The cylindrical aperture

is adapted to receive a screw such as 114, which cooperates with the square nut 115 fitted in said aperture 113. The positioning of the square nut 115 in the square aperture 113 permits the tightening of the screw 70 114 on said nut, inasmuch as the nut is prevented from rotating in the square aperture because the size of the aperture is just large enough to accommodate the square nut. The screw 114 and its associated nut 115 75 are utilized to secure to the flange 116 of the receptacle the housing or covering 117 which functions to completely cover the terminal connections of the fuse receptacle, as clearly illustrated in the upper left-hand fuse receptacle of Fig. 15 and the fuse receptacles 80 illustrated in Figs. 2, 5, and 6.

The housing 117 is provided with an upper flat face 118 which is provided with an enlargement at 119 apertured at 120. The 85 inner surface of said housing is shaped to conform to the contour of the flange 116 of the fuse receptacle 74. Integral with the housing is a forwardly extending portion 121, the base of which is provided with the slots 122 and 123 which serve to fit over the fuse receptacle terminal conducting bars 48. The housing 117, as clearly illustrated in Fig. 18, can be removably attached to the 90 fuse receptacle 112 by means of the screw 114, the screw 114 passing through the aperture 120 and firmly securing the housing 117 to the fuse receptacle by means of its associated nut 115. Obviously when the housing 117 is secured to the fuse receptacle, the fuse 95 receptacle conducting bar terminals 48 will be completely covered, as clearly illustrated in Fig. 2.

Attention is now directed to Figs. 2, 4, 27, 28, 29 and 30 which illustrate an assembled twenty circuit panel board consisting of two four-circuit and two six-circuit neutral units which have been interconnected by standardized conducting means, so as to adapt the assembled unit to a two-wire electrical distributing system. 110

In assembling a panel board of this type, having determined that the ultimate wiring system is to be of the two-wire type, the neutral units are selected of a capacity, the summation of which will give the ultimate capacity of the desired panel board. Obviously, any desired capacity of panel board may be built up and assembled, and the twenty circuit unit herein shown and described has been selected for illustration purposes merely. In assembling this twenty circuit panel board, the four neutral units 10, 11, 12, and 13 equipped with the necessary conducting plates and bars suitable for the ultimate type of circuit controlling apparatus which is to be mounted thereon, or, with this apparatus actually mounted thereon, are assembled into a unitary structure on the mounting channel irons 32 and 33 by 120

means of the mounting plates 76 associated with each neutral unit, the mounting plate 76 being secured to the channel irons 32 and 33 in any desired manner, preferably by nuts and associated bolts 24, as indicated in Figs. 24, 27, and 28. If the neutral units are assembled on the channel irons and secured thereto without the ultimate circuit controlling apparatus in the nature of fuses and switches mounted on the face thereof, it will be evident that this equipment can be secured to the units at any subsequent stage of its construction. Preferably the circuit controlling apparatus on the front of the units is secured thereto, either initially before the panels are assembled on the mounting channel irons or finally as the last act in the assembly operation, after the balance of the equipment has been put in place. When the neutral units have been secured to the channel irons to construct an assembled panel board, as illustrated in Figs. 27 and 28, the assembled panel board is ready to be equipped with a standardized means required to adapt the assembled board for some particular type of commercial electrical wiring system.

In the particular instance now being described, the board is to be adapted to a two-wire distributing system. For this purpose the several conducting plates 55 and 62 associated with the units 10 to 13 inclusive, must be associated with the necessary standardized conducting means, so that these plates will be connected to the common bus bars which feed the assembled panel.

These standardized means which serve as the interconnecting link between the conducting plates 55 and 62 and the common bus bars, are so designed that the common bus bars will not require any lateral bends, or, in other words, so that these bus bars will be confined throughout their length between vertical planes divided substantially by the width of the bus bars. The standardized interconnecting links serving to connect the conducting plates 55 and 62 with the common bus bars 126 and 125 are illustrated in enlarged perspective in Figs. 29 and 30.

The two standardized interconnecting straps, as illustrated in Figs. 29 and 30, are all that are required to adapt the assembled panel board to a two-wire electrical distributing system. These standardized interconnecting straps are so designed that the common bus bars 125 and 126 will have no lateral bends whatsoever and will contain but one vertical bend where these bus bars pass by the barrier 37 and upwardly onto the face of the base 127 of the tail unit 36, where they are connected to the terminal switch 128, which serves to interconnect the panel board through the terminals 129 and 130 with the source of supply. The standardized interconnecting strap 131, illustrated in Fig. 30,

is equipped with perforations such as 132 and 133 which are adapted to cooperate with the threaded perforations 69 in the conducting plates 55, the perforations 132 aligning with the threaded perforations 69 of one conducting plate 55, and the perforations 133 aligning with the threaded perforations 59 of the conducting plate 55 positioned directly alongside of the first plate. The standardized conducting plates 131, therefore, have their perforations 132 and 133 aligning with the perforations of a pair of conducting plates 55 and are secured to said pair of plates 55 by means of suitable screws such as 134.

The plate 131, as illustrated in Fig. 30, consists of the flat portion 135, the right angular extending portion 136 and the bent back part 137, which is bent over and extends at right angles to the portion 136. The part 137 is fitted with a perforated aperture 138, the common bus bars being secured to the part 137 by means of screws such as 139 which cooperate with the threaded aperture 138. The standardized conducting bar 140, illustrated in Fig. 29, is similar to the bar shown in Fig. 30, except that it is but half as wide and fitted with but one perforation 132 and one perforation 133. It comprises a flat portion 141 similar to the portion 135 of the bar 131, an upwardly extending right angular portion 142 similar to the part 136 of the bar 131, and a part 143 bent back at right angles to the part 142, which is similar to the part 137 of the bar 131. Part 133 is fitted with a threaded perforation 138 which is utilized, together with the screw 139 to secure the common bus bars thereto.

The standardized conducting bar shown in Fig. 29 is utilized only at the end of a standardized unit where a single plate 62 is used and which is not associated with a second plate 62 to form a plate which is the equivalent of plate 55. Thus for example, in Fig. 28 the extreme upper standardized and the extreme standardized lower conducting bars are of the 140 type, whereas, all the other standardized conducting bars are of the 131 type. Where two standardized neutral units are united, as for example the union 144 between the units 12 and 13, the two associated conducting plates 62, which unite to make a plate such as 55, are interconnected to a standardized interconnecting bar of the 131 type. When all of the conducting plates 55 and 62 have secured thereto the associated standardized conducting bars of the 131 and 140 type, the common bus bars 125 and 126 can be placed in position on the portions or sections 137 and 143 of these various bars, and then secured thereto by means of the screws 139. When the common bus bars are thus positioned on the back of the assembled panel board by means of

the standardized conducting bars 131 and 140, the circuit controlling apparatus mounted on the front of the panel board will be interconnected by means of the conducting plates mounted on the neutral unit and the standard conducting bars 131 and 140 and the common bus bars 125 and 126 into a two-wire electrical distributing system. These bus bars, depending upon the type of tail piece that is utilized, may end directly in terminals which are connected to the source of power, or they may be connected to a double pole switch 128, as illustrated in Fig. 2, or they may be connected to any other type of terminal apparatus involving fuses and switches. The tail piece which is associated with the assembled panel board is secured to the mounting channel arms 33 and 34 whereby the tail piece, together with the assembled standard units 10, 11, 12, and 13, all constitute an integral unit when thus assembled on the mounting channel irons 33 and 34.

As will be evident from the foregoing description and the accompanying illustrations, the common bus bars 125 and 126 are not fitted with any lateral bends and contain but one vertical bend at 145 (see Fig. 38) where the said bus bars pass from the rear 25 of the assembled units onto the front face of the tail piece. This is a decided manufacturing advantage in that no complicated forming is required in the manufacture of these bus bars. In making these bus bars ordinary copper bar strap can be utilized 30 perforated at the proper places so as to provide for interconnection between the common bus bars and the standardized conducting straps or bars 131 and 140. The vertical bend 145, which is the only bend necessary throughout the entire length of the bus bar, is the simplest bend that can be made, and this bend can be very readily accomplished by those skilled in the art in an ordinary vice and without the use of complicated forming tools. The cost of producing the common bus bars for a system of this type is, therefore, reduced to an absolute minimum.

When the common bus bars have been placed in position on the standardized conducting bars, these common bus bars will be suspended in a horizontal plane, which lies just above the upper surface of the mounting channels 32 and 33. The position of these common bus bars is attained, due to the formation of the mounting plates 76, whereby the lower face of the base 41 of the neutral units is raised above the top face 35 of the mounting channel irons 32 and 33 by a distance substantially equal to the height of the standardized conducting bars 131 and 140.

When the panel board has been thus assembled with the standardized neutral units 40 10, 11, 12, and 13, and the tail units 36 all rigidly secured to the mounting channel irons 32 and 33 and with the common bus bars positioned and placed by means of the standardized conducting straps or bars 131 and 140, the complete assembled unit is surrounded by a suitable barrier frame which is likewise attached to the channel irons 32 and 33. The barrier frame is secured around the assembled panel board by means of corner irons which are illustrated in the panel board assembly in Fig. 3 and in specific detail in Fig. 23.

These corner irons 146 are equipped with a foot 147 secured to the channel iron 32 by 45 means of a screw such as 148. The main portion of the corner iron consists of the plate 149 which carries a slot 150 and a right angular projection 151 which is likewise fitted with a slot 152. The slots 150 and 152 are open at the top. The end pieces of the barrier frame consisting of the plates 26 and 27 carry a bolt 154 which fits into the slots 150 of the corner irons, the plate being secured by means of said bolt 154 and the wing nut 155 to the plate 149 of the corner iron. The sides 28 and 29 of the barrier frame comprise either a single plate of insulating material or preferably a plurality of plates of insulating material such as 156, 157, and 158 (see Fig. 22). These plates of insulating material are secured by suitable nuts such as 159 and associated bolts to a channel iron 160. The plates 156 and 157 composing the sides of the barrier frame adjacent the branch circuit terminals of the fuse receptacles are equipped with notches or slots 161 through which the wires of the branch circuits are carried to the fuse receptacle terminals.

The channel iron 160 is provided and attached to the side member of the carrier frame consisting either of a single plate of insulating material or a plurality of such plates for the purpose primarily of a 50 strengthening or stiffening member. In a long assembled panel board unit the length of these side barrier insulating plates is such as to make it comparatively fragile and likely to be broken very easily, and the channel iron 160 is provided to strengthen and stiffen this side member and to prevent such breakage. Preferably these side members are made up of a plurality of strips of insulating material and in this case the channel iron 160 serves as a suitable means for uniting these various strips into one piece. By making the side member of the barrier frame of a plurality of pieces it is feasible to utilize certain lengths of scrap 55 material for this purpose and thereby effect a considerable saving. In securing the side member of the barrier frame to the corner iron, in view of its length and weight, especially in a large assembled panel board

unit, it is necessary to remove the strain resulting from the weight of said member from the insulating material of which the barrier side member is constructed. This is also accomplished by the channel iron, inasmuch as the channel iron is extended beyond the end of the insulating barrier frame side member and this extended portion is fitted with a bolt 162 and a wing nut 163, which bolt and wing nut cooperate with the slot 152 of the corner iron and serve to secure the side member of the barrier frame in position. This barrier frame side member construction is exceedingly advantageous, therefore, in that the channel iron 160 serves the three-fold purpose of permitting the use of scrap insulating material for the side member barrier, in that it stiffens and strengthens said side member, and in that it serves as a mounting means for said side member, and thereby relieves the comparatively weak insulating material, of which the side member is constructed, of the strain resulting from the weight which must be suspended in mounting said member.

It will be noted from what has just been said in connection with the barrier frame that the end pieces 26 and 37 thereof and the side members 28 and 39 thereof can be readily placed in position on the corner irons secured to the mounting channel irons 32 and 33, after which the assembled panel board is completely equipped and ready to be positioned and placed in the panel box enclosure.

The completed assembled panel board consisting of the standardized units and the tail unit are interconnected, as hereinbefore described, and surrounded by the barrier frame must obviously be properly positioned in the panel box enclosure, so that the equipment mounted on the panel board will properly align and co-operate with the doors 18 and 19 and the frame 22. In order that this assembled unit may be easily and quickly positioned in the panel board enclosure and in order to facilitate the removal of this assembled board entity from the panel board enclosure with an assurance that it can be returned to its proper position, the receiving pockets or shoes 35 are secured to the bottom of the base 14 of the panel board enclosure.

This shoe or pocket is shown in enlarged perspective in Fig. 25 and consists essentially of the mounting flanges 166, 167, and 168 in the nature of brackets which are secured to the bottom 169 of the base 14 of the enclosure. The flanges 166 to 168 are integral with the box-like enclosure consisting of the side pieces 170 and 171 and the base 172 and the front face 173. The box-like enclosure comprising the faces 170, 171, and 172, together with the bottom 169 of

the base 14 will serve as a receiving means for the end of the mounting channels 32 and 33, and consequently function to positively position the assembled panel board unit mounted on said channel irons in its position in the panel board enclosure. (See Fig. 3.) Obviously any other suitable form of receiving pocket or shoe could be used.

As hereinbefore stated, the circuit controlling apparatus which is mounted on the neutral units can be placed thereon at any stage in the operation of assembling the unit. This part of the work is preferably done either initially or as the last operation in the assembly just prior to the time that the frame 22 and its associated doors are mounted on the base 14. The method of mounting the switches and fuses on these neutral bases has been hereinbefore described.

When push button switches are utilized, however, and a dead front panel is desired, such as is illustrated in Figs. 1, 2, and 3, it is considered essential to provide a cover for the switches which will be individual to each pair of switches mounted across the panel board and which cover plates should be preferably provided with interlocking means whereby all of the said covers will be rigidly interconnected, and whereby in the assembled unit the interconnected covers will give the appearance of a single plate. These switch cover plates 38 cooperate with the flanges 39 and 40 secured to the cover to completely obscure from view and from any possibility of contact all current and potential carrying parts when the inner door 19 only is opened, as illustrated in Fig. 1.

The preferred form of switch plate cover construction utilized with this type of panel board is illustrated in Fig. 26. As there shown, each of these plates 38 comprises at one lateral edge a U shaped trough 174 and have the other lateral edge turned down substantially normal to the face of the plate as shown at 175. Each of these plates, as shown in Figs. 2, 3, and 10, are apertured to permit the projection thereto of the operating push buttons of the switches. When the switch cover plates 38 are assembled, the portion 175 of one plate is fitted in the U shaped trough 174 of the next plate and so on throughout the entire panel. This interconnection between the U shaped trough 174 of one plate and the lateral down turned edge 175 of the next plate serves to form a rigid interconnection between all of the plates and serves to positively position the plates together with the push buttons of the switch. Further, because of the arcuated formation of both lateral edges of each of said plates, the assembled switch plates 38 give the general appearance of a single plate. Likewise, if desired, any of said plates 38 can

be readily removed by the proper authorized party, if repairs to the switch are desired, by swinging the said plate out of the position shown in broken lines for one of said plates 38, as illustrated in Fig. 26. When the plate is thus pulled out the U shaped trough portion can readily be slipped out of the right angular lateral projection of the next adjacent plate, and in a similar manner the plate 38 thus removed can readily be reinserted in place without interference with any of the other switch plates in the assembled structure.

- 17 After the panel board assembly secured to the channel irons 32 and 33 and equipped with all the circuit controlling apparatus, hereinbefore described, is placed in position in the panel box enclosure by the aid of the guiding shoes 35, the assembled unit is secured in position by means of the screws 34. The cover 15 is next secured in position by means of the screws 17 and when thus positioned, due to the automatic proper positioning of the assembled unit, by means of the shoes 35, the doors 18 and 19 assume their proper places with respect to the equipment. Likewise, the flanges 39 and 40 cooperate with the assembled switch cover plates 38 and the barriers 26 and 37 to positively enclose the opening provided by the inner door 19, so that access is permitted only to the switch operating buttons.

- 35 The method of assembly for the built up panel units is identical in all respects for each unit irrespective of the system of electrical distribution with which it is ultimately to be used, with the exception that the character and disposition of the standardized interconnecting links, straps or bars used for each such assembly will vary according to the electrical distributing system desired. Obviously, the tail pieces or units will also change with the electrical distributing system used, and the character of the circuit controlling apparatus mounted on the neutral nunits may be altered, as hereinbefore described. It is, therefore, unnecessary to describe in detail the method of assembling the built up panel board for each type of electrical distributing system to which the standardized equipment and the neutral standardized unit herein disclosed is adapted, and hence in the following description that part only of the assembly which is special to each particular electrical distributing system will be directed in detail.

- 45 Attention is now directed to Figs. 31 to 38 inclusive which illustrate the standardized conducting bar, bus bar and tail unit equipment for a built up standardized panel equipment adapted to be used with a three-wire distributing system and a convertible three-wire to two-wire system and a two-wire to three-wire system.

Fig. 31 is a rear view of the assembled equipment and shows the standardized neutral units 10, 11, 12, and 13 mounted and secured as hereinbefore described on the mounting channel irons 32 and 33. In order to interconnect the conducting plates 55 and 62 of the assembled standardized neutral units with the common bus bars 176, 177, and 178 of a three-wire system four types of standardized conducting bars or straps, 75 illustrated in perspective in Figs. 34, 35, 37, and 38 will be utilized. These standardized conducting bars or straps are so designed that when they are positioned and secured to conducting plates 62 and 65 and 80 the common bus bars 176-178 inclusive are attached thereto, as illustrated in Fig. 31, the bus bars will be so spaced with respect to each other that they may be carried directly without any lateral bends to 85 the terminals of a standard three-blade switch. In other words, the common bus bars 176-178 inclusive will be spaced on centers when positioned, as shown in Fig. 31, on the standardized conducting straps 90 which are equal to the centers on which the blades of a standard three blade switch are positioned.

This wiring is accomplished by the standardized conducting straps which are confined to two shapes, one of which shapes is illustrated by the conducting strap shown in Figs. 34 and 37, and the other by the conducting strap illustrated in Figs. 35 and 36. The straps 179 and 180 are used to connect 100 the conducting plates 55 and 62 with the two outer common bus bars 176 and 178, the strap 179 interconnecting with the conducting plates 55 or a pair of conducting plates 62, and the strap 180 with a single conducting plate 62. The standard straps 179 and 180 are of a substantial U-shape and serve to extend the arms 59 and 64 of the conducting plates 55 and 62 outwardly so that when the common bus bars 176 and 178 are 110 connected to the upper portion 181 and 182 respectively of the straps 179 and 180, these common bus bars will be positioned at centers corresponding to the outer blades of the standard three-blade switch. Each of 115 these conducting bars is perforated at 183 to receive the screw such as 184, whereby these bars are attached to the conducting plates 55 and 62, and each of the bars, also, is fitted with a threaded perforation at 185, 120 this threaded perforation cooperating with the perforation of the common bus bars and a screw such as 186 to secure the common bus bars to each of these standardized connecting straps or bars. The center or neutral bus bar 177 is secured to the conducting plates 62 and 55 by a conducting strap which spans a pair of such conducting plates.

125 This conducting strap 187, which cooper- 130

ates with the plates 55, is illustrated in Fig. 35, and the conducting strap 188, which co-operates with the conducting plates 62, is illustrated in Fig. 36. These conducting straps 187 and 188 are substantially of an inverted V shape and are each fitted with a high portion 189 and 190 respectively, which are fitted with threaded apertures 191 and 192 respectively, adapted together with a screw such as 186 to attach the perforated neutral bus bar 177 to the conducting straps. The conducting bars or straps 187 and 188 are also fitted with perforations 193 at their lower extremities or feet 194 whereby these straps are secured and attached to the conducting plates 62 and 55. When the standard conducting straps are attached to the conducting plates 55 and 62 and the common bus bars 176 to 178 attached to the standardized conducting straps, as illustrated in Fig. 31, the built up panel board is adapted for a three-wire electrical distributing system.

Obviously when the assembled panel is thus wired for a three-wire electrical distributing system, a tail unit 195 of the type illustrated in Fig. 32 must be used. A tail unit like 195 is used in the event that a three-pole switch like 196 is desired, but obviously, as hereinbefore described, this tail unit may be equipped with terminals only or with terminals and fuses or a switch and fuses, depending absolutely upon the commercial demand.

When the neutral units of the built up panel are fitted with the standardized interconnecting links, as shown in Fig. 31, it will be evident that the uppermost fuse receptacle on each side of the board is connected to the central neutral bus bar 177; that the next two fuses beneath on one side of the board are connected to the common bus bar 176, and the next two fuses beneath on the other side of the board are connected to the common bus bar 177. Likewise, that the next two fuses on both sides of the board are connected to the neutral bus bar 177, and that in this manner the connection between the fuses or circuits and the central or neutral bus bar and the two line or outside bus bars 176 and 178 will alternate throughout the length of the board. The wiring connection will be very apparent to those skilled in the art by referring to Figs. 5, 7, and 31, and consequently further description thereof is deemed unnecessary.

When it is desired to convert the assembled panel board for three-wire distribution, as illustrated in Fig. 31, to a two-wire distribution, it is merely necessary to change the tail unit connection. Thus for example, when this change is desirable, the tail unit used with a three-wire electrical distribution system, illustrated in Fig. 32, is re-

placed by the tail unit 197, as shown in Fig. 33, in which the two common line bus bars 176 and 178 are interconnected by a conducting strap 198. This, in effect, makes these two bus bars a single bus bar, which constitutes one side of the line, the other side of the line being the neutral bus bar 177. When thus interconnected, the connection, as illustrated in Fig. 31, will constitute a two-wire electrical distributing system. The ends of the common bus bars 176 to 178 inclusive may then be interconnected by a switch such as 199 as illustrated in Fig. 33, or any other desired type of terminal interconnection can obviously be used.

The description thus far has demonstrated how the standardized equipment utilized to assemble a built up panel can be combined to construct a panel board adapted for either two-wire, three-wire, or convertible two to three-wire and three to two-wire systems.

In Figs. 39 to 43 inclusive is illustrated the equipment required, in addition to the standard equipment hereinbefore described, for adapting a built up panel board composed of neutral standardized units to a three-phase distributing system. The only additional equipment required for adapting the assembled standardized neutral units to a three-phase distributing system are the standardized interconnecting straps, bars, or links illustrated in perspective in Figs. 40 to 43. The standard conducting strap 200, illustrated in Fig. 40, is used to connect a pair of contact plates such as 55 to either one of the outside common bus bars 201 or 202 (see Fig. 39). The standard conducting strap or interconnecting link 203, illustrated in Fig. 41, is of the same shape as the standardized interconnecting link illustrated in Fig. 40, but is of but half the width of said link or strap, being utilized for the same purpose as the strap 200 with pairs of connecting plates 62. The flat portion 204 of the interconnecting strap 200 contains perforations 205 which cooperate with screws such as 206 to attach the said strap to the interconnecting plates 55, the perforations 205 aligning with the perforations 69 in the said plates. Integral with the plate 204 and extending upwardly in an oblique direction therefrom is the portion 207 which has secured thereto the flat portion 208 fitted with a threaded perforation at 209 adapted to receive the screw 210 which attaches the common bus bars such as 201 or 202 to the strap 200.

In a like manner the conducting strap 203 comprises the flat portion 211 carrying similar perforations 205 and fitted with the oblique upwardly extending section 212 and the flat portion 213 carrying the threaded perforation 214.

The standardized conducting intercon-

necting link or strap 215, illustrated in Fig. 42, is utilized to connect the center common bus bar 216 to one of the standardized conducting plates 55, and also serves the purpose of interconnecting one of said plates 55 with either one of the outer common bus bars 201 or 202, (see Fig. 39). The standardized strap 215 consists of the flat portion 217 carrying the perforations 218 which cooperate with screws 206 to secure said strap 215 to a conducting plate 55. Integral with and extending obliquely upward from the flat portion 217 is the part 219, integral with which is the flat portion 220 fitted with the threaded perforation 221. The flat portion 220 carries the common bus bars, these bus bars being secured to said flat portion by means of screws such as 222. The standardized interconnecting link or bar 223, illustrated in Fig. 43, is of the same shape as the standard bar 215, and is used for the same purpose in connection with the connecting plate 62 and comprises the flat base portion 224 perforated at 225, the oblique upwardly extending portion 226 and the top flat portion 227 fitted with the threaded perforation 228.

When a built up panel board consisting of neutral standardized units is to be wired for three-phase distribution, it is necessary first to determine how the circuits are to be distributed among the various phases and when the character of distribution of the circuits has been determined, the circuit plan distribution can be readily put into effect by the standardized interconnecting links 200, 203, 215, and 223. For the twenty circuit unit, illustrated in Fig. 39, for the purpose of illustration, we will consider the phase between the common bus bars 202 and 216 as the A phase; the circuit between the common bus bars 201 and 216 as the B phase, and the circuit between the common bus bars 201 and 202 as the C phase. The circuit arrangement illustrated in Fig. 39 is designed to distribute the twenty circuits throughout the three phases as equally as possible, and in the interconnections there shown, there are seven circuits connected on the A phase; seven on the B phase, and six on the C phase. Obviously any other desired distribution of the circuits between the phases, depending upon commercial requirements, could be obtained by means of the standardized interconnecting links 200, 203, 215, and 223. In the particular distribution shown in Fig. 39, when the board is viewed from the front, the circuits on the left hand side of the board beginning with the upper circuit will be connected in the various phases as follows: The first two circuits in the C phase; the next four circuits in the A phase; the next two circuits in the C phase, and the next two circuits in the A phase. On the right side of the board, the upper three

circuits are in the B phase; the next two circuits in the C phase; the next four circuits in the B phase, and the bottom circuit in the C phase. The system of interconnection between the common bus bars 201, 202, and 216 through the standardized interconnecting links 200, 203, 215, and 223, and the several conducting plates 55 and 62 associated with the neutral units to the circuit controlling equipment mounted on the face of the unit, for this three-phase system will be readily apparent to those skilled in the art from an inspection of Figs. 3, 5, 6, and 39.

The tail unit utilized with the equipment illustrated in Fig. 39, in case a switch is desired, will obviously be of the type illustrated in Fig. 32, it being understood, however, that any other type of terminal equipment can be readily utilized. It should be noted, also, in this connection that the common bus bars 201, 202, and 216 are all of the type illustrated in Fig. 38 and have no lateral bends throughout their length and have only one vertical bend at 145 where the bus bars are turned up to rest on the face of the tail unit.

The method of interconnecting the assembled twenty-circuit panel board, so that it is adapted for four-wire three-phase distribution, will next be described in connection with Figs. 44 to 49 inclusive. For this purpose, four standardized interconnecting links or bars, as illustrated in perspective in Figs. 46 to 49 inclusive, are required. The standardized interconnecting link 229, illustrated in Fig. 46 is shaped in cross-section comprising the foot portion 230 carrying the perforations 231, the upright portion 232 and the top flat portion 233 are fitted with a threaded aperture 234. The top portion 233 carries the common bus bars, these bus bars being attached to this top portion by screws such as 235. The standardized interconnecting link 236, illustrated in Fig. 47, consists of the foot portion 237 perforated at 238 integral with which is the upright portion 239 carrying the flat upper portion 240 fitted with the threaded perforation 241. The flat portion 240 carries the common bus bars which are attached thereto by means of screws such as 235.

The standard interconnecting link 242 illustrated in Fig. 48 consists of the lower flat portion 243 perforated at 244 and the upper flat portion 245 fitted with the threaded perforation 246, the parts 243 and 245 being integral with and interconnected by the oblique upwardly extending part 247. The flat portion 243 is adapted by means of its perforations 244 to cooperate with two plates such as 55, the perforations 44 aligning with the threaded perforations 69 in the two plates 55. The upper flat portion 245

is adapted to carry the common bus bar, to which it is attached by means of screws such as 235.

The standardized interconnecting link 248 illustrated in Fig. 49, is similar in shape to the link illustrated in Fig. 48, but of half the width, and comprises the lower flat portion 249, the upper flat portion 250, and the integral interconnecting link 251. The lower flat portion 249 is fitted with perforations 244 and the upper flat portion 250 is equipped with a threaded perforation 246.

The four standardized interconnecting links or conducting bars, illustrated in Figs. 46 to 49 inclusive, can be used to connect the controlling apparatus mounted on the standardized neutral panel units in a four-wire three-phase distributing system. Obviously in a four-wire three-phase distributing system, as was the case in connection with the three-phase distributing system, it is essential to determine initially how the circuits on the panel are to be distributed, after which the standardized interconnecting links can be united with the conducting plates 55 and 62 to obtain this desired distribution.

In the illustration shown in Fig. 44, the common bus bars 252, 253, 254, and 255 are interconnected by the standardized interconnecting links to the conducting plates for the purpose of illustration so that seven circuits are connected to the A phase; seven circuits to the B phase, and six circuits to the C phase; the A phase constituting the circuit between the common bus bars 254 and 255; the B phase constituting the circuit between the common bus bars 253 and 255, and the C phase constituting the circuit between the common bus bars 252 and 255. In the particular distribution selected for purposes of illustration in Fig. 44, the equipment is connected into these three phases when the said equipment is viewed from the front of the board as follows: Considering the left side of the board the first three circuits are connected to the A phase; the next two to the C phase, the next four to the A phase, and the lowermost circuit to the C phase. On the right side of the board the first three circuits are connected to the B phase; the next two circuits to the C phase; the next four circuits to the B phase, and the lowermost circuit to the C phase. The method in which the common bus bars 252 to 255 inclusive are interconnected by the standardized interconnecting links or bars 229, 236, 242, and 248 to the conducting plates 55 and 62, in order to obtain this illustrative type of distribution of circuits, will be clearly evident to those skilled in the art from an inspection of Fig. 44, and consequently further description thereof is considered unnecessary.

The tail unit utilized in connection with

the four-wire three-phase distributing system will obviously depend upon the terminal connections desired. If a switch is desired the equipment would be of the type illustrated in Fig. 45 in which the base 260 of the tail unit is fitted with a three-blade switch 261 and in which the common bus bars 252 to 254 are connected through this switch to the line terminals 262, 263, and 264 respectively. The common bus bar 255 is carried right through on the face of the tail panel unit 260 and terminates in the line terminal 265.

It will now be apparent from the foregoing description that by the use of standardized units comprising neutral panel board units adapted to carry or mount different types of electrical controlling apparatus, standardized interconnecting means comprising links or conducting bars which can be interchangeably connected to said neutral units and the use of the common commercial bus bar strap, that built up panel boards can be constructed of any desired capacity and adapted for interconnection to any of substantially all the commercial types of electrical distributing systems. The panel board problem, according to the teachings of this invention, has consequently been reduced to an assembling operation whereby the ordinary unskilled assembly operator is in the position to assemble a built up panel board of any capacity and for substantially any electrical distribution system from standardized parts which may be drawn from stock. The standardized parts which are used in the construction of a built up panel board of this type constitute 90% of the material entering into the construction of the board and only the remaining 10% of the equipment utilized in the construction and assembly of a board of any type is special to the panel board. This special apparatus is not of a complicated nature and consists principally in the common bus bars made from ordinary commercial bus bar strap, which bus bars must be perforated so that they can be attached by means of screws to the standardized interconnecting links or conducting bars secured to the back of the neutral standardized panel board units. The remarkable flexibility of this stock system, because of its adaptation to substantially all the requirements of service, as hereinbefore described, will consequently be apparent.

Obviously the invention is not limited to the specific embodiments thereof herein illustrated and described but is capable of many variations and other applications within the spirit and scope thereof, as set forth in the following claims:

Having thus described my invention, what I claim is new and desire to secure by Letters Patent is:

1. In a panel-board art, a structure comprising a plurality of portable interfitting basic units of varying capacities, circuit controlling apparatus mounted on each of said units, conducting plates positioned on said units having arms thereof on each side of said units, said conducting arms on the front of said units being electrically connected to said circuit controlling apparatus, and means 10 adapted to be removably connected to the said conducting arms on the rear face of said units, whereby said circuit controlling apparatus can be interconnected in any one of a desired plurality of electric wiring systems. 15
2. In the panel-board art, a plurality of portable basic units of varying capacities, circuit controlling apparatus mounted on each of said units, said units being usable 20 individually or in combination to provide a panel-board of greater capacity than a single unit, a bus-bar system common to said plurality of basic units, and means removably connected to said units, whereby said bus-bar system can be connected to said circuit controlling apparatus in any one of a desired plurality of electric wiring systems. 25
3. In the panel-board art, a plurality of basic units of similar construction, but of 30 varying capacities, circuit controlling apparatus corresponding to the capacity of each unit mounted on such unit, branch wire terminals connected to said circuit controlling apparatus, conducting plates passing through said units and having portions thereof positioned on either face of said units, a bus-bar system common to said plurality of basic units, and means adapted to interconnect said bus-bar system to said conducting plates, so as to include said circuit controlling apparatus in any one of a desired plurality of electric wiring systems. 40
4. In the panel-board art, a plurality of portable basic units, circuit controlling apparatus mounted on each of said units, means for mechanically holding a plurality of said basic units in assembled relation to form a panel-board, conducting plates passing through each of said units and having portions thereof positioned on each face of said units, the circuit controlling apparatus being connected to the portions of said plates positioned on the front faces of said units, a bus-bar system common to all of said units, 50 and means adapted to interconnect said system to the portions of said conducting plates positioned on the rear face of said units, whereby the circuit controlling apparatus mounted on said units can be included in any one of a desired plurality of electric wiring systems. 60
5. In the panel-board art, a plurality of basic panel-board units, circuit controlling apparatus mounted on each of said units, 65 terminal connections for said circuit controlling apparatus extending to the rear face of said units, means to secure two or more of said units in assembled relation, common bus-bars for said basic units, and a plurality of different and specially shaped means to interconnect said bus-bars to said terminal connections in any desired one of a variety of electric wiring systems, said interconnections being readily removable to facilitate interchangeability. 70
6. A panel-board of the type described, comprising in combination a plurality of unitary sections, each of which constitutes a neutral panel-board section, a plurality of circuit controlling appliances mounted on each such section, means for assembling one or a plurality of such sections into a panel-board of the capacity of one or the combined capacities of the several sections, conducting means connected to each of said circuit controlling appliances extending through said sections to the rear face thereof, bus-bars common to all of said sections, and standardized means adapted to interconnect said circuit controlling appliances to said bus-bars in any one of a variety of electric wiring systems, said interconnections being readily removable to facilitate interchangeability. 75
7. A panel-board of the type described, comprising in combination a plurality of portable unitary sections, a plurality of circuit controlling appliances on each section, means to secure the plurality of sections in assembled relation, a plurality of bus-bars common to said plurality of sections, and standardized means adapted to interconnect said circuit controlling appliances to said bus-bars in any one of a variety of electric wiring systems, said interconnections being readily removable to facilitate interchangeability. 80
8. In the panel-board art, a plurality of basic units, circuit controlling apparatus mounted on the front face of said units, means to conductively extend the electrical connection to said circuit controlling apparatus to the rear face of said units, a plurality of common bus-bars for said units, each of said bus-bars being confined throughout its length between vertical planes separated by substantially the width of said bus-bars, and means whereby said bus-bars are adapted to be connected to the conductive means extending to the rear face of said units in any one of a desired plurality of electric wiring systems. 110
9. In the panel-board art, a structure comprising a plurality of portable interfitting basic units, circuit controlling equipment mounted on the front of each of said units, conducting bars electrically connected to said equipment terminating on the rear of each of said units, a bus-bar system for said units, and means whereby said bus-bar sys- 115 120 125 130

tem can be connected to the said conducting bars either in two-wire, three-wire, three-phase or four-wire three-phase relationship.

10. In the panel-board art, a structure comprising a plurality of portable interfitting basic units, circuit controlling equipment mounted on the front of each of said units, conducting bars electrically connected to said equipment terminating on the rear of said units, a bus-bar system for said units, and means comprising standardized conducting straps whereby said bus-bar system can be connected to the said conducting bars, either in two-wire, three-wire three-phase or four-wire three-phase relationship.

11. In the panel-board art, an assembled panel-board consisting of a plurality of portable basic units, fitted with circuit controlling apparatus, a current conducting system comprising common bus-bars, standardized conducting bars variously shaped connected to said bus bars to secure the desired type of electric wiring system for said circuit controlling apparatus, and standardized conducting plates interconnecting each of said standardized conducting bars with the terminals of said circuit controlling apparatus.

12. In the panel-board art, an assembled panel-board consisting of a plurality of portable basic units, fitted with circuit controlling apparatus, a current conducting system comprising common bus bars, said bus bars being confined throughout their length between vertical planes separated by substantially the width of the said bus bars, standardized conducting bars variously shaped removably connected to said bus bars to secure the desired type of wiring system for said circuit controlling apparatus, and standardized conducting plates interconnecting each of said standardized conducting bars with the terminals of said circuit controlling apparatus.

13. In the panel-board art, a structure comprising a plurality of portable interfitting basic units, circuit controlling equipment mounted on the front of each of said units, conducting bars electrically connected to said equipment terminating on the rear of said units, a bus-bar system for said units, and means comprising seven different types of standardized conducting straps, whereby said bus-bar system can be connected to said conducting bars in either two-wire, three-wire, three-phase or four-wire three-phase relationship.

14. In the panel-board art, an assembled panel-board consisting of a plurality of portable basic units fitted with circuit controlling apparatus, a current conducting system comprising standardized conducting plates connected to said circuit controlling apparatus, a pair of common bus bars, and stand-

ardized conducting bars all of the same shape interconnecting said bus bars and said conducting plates, whereby said circuit controlling apparatus is connected into a two-wire electric distributing system.

15. In the panel-board art, an assembled panel-board consisting of a plurality of portable basic units fitted with circuit controlling apparatus, a current conducting system comprising standardized conducting plates connected to said circuit controlling apparatus, a pair of common bus bars, said bus bars being confined throughout their length between vertical planes separated by substantially the width of the bus bars, and so standardized conducting bars all of the same shape each having a U shaped end interconnecting said bus bars to said conducting plates, whereby said circuit controlling apparatus is connected into a two-wire electric distributing system.

16. In the panel-board art, an assembled panel-board consisting of a plurality of portable basic units fitted with circuit controlling apparatus, a current conducting system comprising common bus bars, standardized conducting bars variously shaped connected to said bus bars to secure the desired type of electric wiring system for said circuit controlling apparatus, and standardized conducting plates interconnecting each of said standardized conducting bars with one terminal each of two pieces of said circuit controlling apparatus mounted on said panel-board.

17. In the panel-board art, a structure comprising a plurality of portable interfitting basic units, each unit consisting of a perforated base of insulating material, U shaped conducting plates fitted in said perforations having arms resting on both the front and rear faces thereof, other U shaped conducting plates fitted in perforations extending inwardly from the top and bottom edges of each of said bases, the two adjoining plates in adjacent units when assembled end to end in a panel-board combining to form a single plate similar to the said first mentioned U shaped conducting plate.

18. In the panel-board art, a structure comprising a plurality of portable interfitting basic units, each unit consisting of a perforated base of insulating material, U shaped conducting plates fitted in said perforations having arms resting on both the front and rear faces thereof, other U shaped conducting plates fitted in perforations extending inwardly from the top and bottom edges of each of said bases, the two adjoining plates in adjacent units when assembled end to end in a panel-board combining to form a single plate similar to the said first mentioned U shaped conducting plates, circuit controlling apparatus positioned on the front of said base, the arms of the com-

- bined plates at the top and bottom of adjacent units and the first mentioned **U** shaped plates each being electrically connected and common to one lead each of two adjacent pieces of apparatus.
19. In the panel-board art, a structure comprising a plurality of portable interfitting basic units, each unit consisting of a perforated base of insulating material, **U** shaped conducting plates fitted in said perforations having arms resting on both the front and rear faces thereof, other **U** shaped conducting plates fitted in perforations extending inwardly from the top and bottom edges of each of said bases, the two adjoining plates in adjacent units when assembled end to end in a panel-board combining to form a single plate similar to the said first mentioned **U** shaped conducting plates, circuit controlling apparatus positioned on the front of said base, the arms of the combined plates at the top and bottom of adjacent units and the first mentioned **U** shaped plates each being electrically connected and common to one lead each of two adjacent pieces of apparatus, common bus bars for said plurality of units, and means electrically connected to the arms of the combined plates and the first mentioned plates to interconnect the circuit controlling apparatus mounted on said units to said common bus bars in any one of a desired plurality of electric wiring systems.
20. In the panel-board art, a structure comprising a plurality of portable interfitting basic units, each unit consisting of a perforated base of insulating material, **U** shaped conducting plates fitted in said perforations having arms resting on both the front and rear faces thereof, other **U** shaped conducting plates fitted in perforations extending inwardly from the top and bottom edges of each of said bases, the two adjoining plates in adjacent units when assembled end to end in a panel-board combining to form a single plate similar to the said first mentioned **U** shaped conducting plate, circuit controlling apparatus positioned on the front of said bases, the arms of the combined plates at the top and bottom of adjacent units and the first mentioned **U** shaped plates each being electrically connected and common to one lead of two adjacent pieces of apparatus, common bus bars for said plurality of units, and standardized conducting bars variously shaped removably connected to the arms of the combined plates and the first mentioned **U** shaped plate to interconnect the circuit controlling apparatus mounted on the said units in any one of a desired plurality of electric wiring systems.
21. In the panel-board art, a portable insulating plate fitted with a plurality of perforations, conducting plates adapted to pass through said perforations and equipped with
- arms positioned on each side of said plate, circuit controlling apparatus secured to said conducting arms positioned on the front face of said plate, and conducting means adapted to be removably secured to the said conducting arms positioned on the rear of said plate, said conducting means being variously shaped and standardized for adaptation to different systems of electric interconnection or wiring.
22. In the panel-board art, a portable insulating plate fitted with a plurality of perforations, conducting bars adapted to pass through said perforations, and equipped with arms positioned flatly on each side of said plate, circuit controlling apparatus secured to said conducting arms on the front face of said plate, common bus-bars, and variously shaped and standardized conducting means adapted to interconnect said bus-bars and the conducting arms on the rear face of said plate, said connection being readily removable to facilitate interchangeability.
23. In the panel-board art, a portable basic unit, circuit controlling appliances mounted on the front face of said unit, conductive means connected to said circuit controlling appliances extending through said unit to the rear face thereof, and a plurality of different and specially shaped standardized means adapted to be connected to said first named means to electrically fit the said circuit controlling apparatus of the said unit for connection in any one of a desired plurality of electric wiring systems.
24. In the panel board art, a basic portable unit comprising an insulating base fitted with perforations, conducting bars positioned in said perforations having an arm positioned on both the front and rear faces thereof, circuit controlling apparatus electrically connected to the arms on said front face, a reinforcing frame secured to said base, and means associated with said frame adapted for mounting said unit.
25. In the panel-board art, a basic portable unit comprising an insulating base fitted with perforations, **U** shaped conducting bars positioned in said perforations having an arm resting on both the front and rear faces thereof, circuit controlling apparatus on the front of said base, each of said arms on the front of said base being electrically connected and common to one lead each of two adjacent pieces of said apparatus.
26. In the panel-board art, a basic portable unit comprising an insulating base fitted with perforations having an arm positioned on both the front and rear faces thereof, circuit controlling apparatus on the front of said base, each of said arms on the front of said base being electrically connected and common to one lead each of two adjacent pieces of said apparatus, and means as-

sociated with said frame adapted for mounting said unit.

27. In the panel-board art, basic portable units each comprising an insulating base 5 fitted with perforations, circuit controlling apparatus positioned on the front of each of said bases, terminals therefor mounted on the front of each of said bases, U shaped conducting plates fitted in said perforations having arms resting on both the front and rear faces of each of said bases, the arms on the front face of each of said bases being electrically connected and common to one terminal each of two adjacent pieces of said apparatus, and other U shaped conducting plates positioned in perforations extending inwardly from the top and bottom edge of each of said bases connected to a terminal of each of the pieces of circuit controlling apparatus adjacent to the ends of juxtaposed bases.

28. In the panel board art, a plurality of basic portable units consisting of insulating bases, circuit controlling apparatus mounted 25 on the front faces of said bases, reinforcing frames secured to each of the rear faces of said bases, channel irons, and means cooperating with said reinforcing frames and

said channel irons for mounting said bases upon said channel irons. 30

29. In the panel board art, a basic portable unit comprising an insulating base, circuit controlling apparatus mounted on the front face of said base, longitudinal mounting members adapted for mounting said base, and a reinforcing frame secured to the rear face of said base and spacing said unit forwardly a predetermined distance from said longitudinal mounting members. 35

30. In the panel board art, a basic portable unit comprising an insulating base, circuit controlling apparatus mounted on the front face of said base, longitudinal mounting members adapted for mounting said base, and a reinforcing frame secured to the rear face 40 of said base and spacing said unit forwardly a predetermined distance from said longitudinal mounting members, said frame comprising spaced parallel plates having longitudinal adjustment on said mounting 45 members and transverse cross-bars to which said unit is fastened. 50

In witness whereof, I have hereunto subscribed my name.

HENRY F. STARRETT.
